UNITED STATES PATENT OFFICE

2,262,388

SHAVING DEVICE

Godfrey Dalkowitz, Brooklyn, N. Y., assignor to
American Safety Razor Corporation, Brooklyn,
N. Y., a corporation of Virginia

Application June 26, 1937, Serial No. 150,497

15 Claims. (Cl. 30—43)

This invention relates to the art of dry shaving in which the shaving operation is effected without any preliminary or auxiliary treatment for the hair such as by the use of shaving soap or cream and in particular it relates to a device having relatively movable parts for effecting a shaving operation by a clipping or shearing of the hair.

Among the general objects of my invention is the provision of a shaving device made of elements which can be manufactured inexpensively, and assembled quickly and economically to provide an efficiently functioning instrument.

For the attainment of these objects and such other objects as will hereinafter appear or be pointed out I have shown several illustrative embodiments of my invention in the drawing, in which:

Figure 1 is a perspective view showing a shaving head according to my invention completely assembled and mounted in a handle;

Figure 2 is a sectional view on an enlarged scale substantially on the line 2—2 of Figure 1 looking in the direction of the arrows;

Figure 3 is an exploded view on a scale larger than that of Figure 1 showing in perspective the component parts of the assembly of Figure 1 constituting the shaving head;

Figure 4 is a sectional view substantially on the line 4—4 of Figure 2 looking in the direction of the arrows;

Figure 5 is a detail view in plan showing the configuration of the hair receiving slots;

Figure 6 is a view similar to Figure 5 showing a modified construction; and

Figure 7 is an end view of a modified construction of shaving head.

By referring to Figure 1 it will be observed that I have there shown a shaving head A that constitutes the subject of my invention mounted in a handle B. The latter feature does not constitute part of my invention and may be dismissed with the general statement that it may be of any suitable or preferred type, such, for example as a casing within which may be positioned a source of motive power, such as an electric motor, for imparting movement to the parts of the shaving head.

My shaving head comprises in general what may be termed a fixed part and a movable part, and the fixed and movable parts are provided with cutting teeth that pass over each other and effect the shearing or clipping action.

The fixed part of my shaving head comprises a member 12 that is shown as positioned in the

middle portion of the shaving head and may be described as being constituted by a central rib or flange 14 having leg portions 16 and 18 depending therefrom and having portions projecting laterally outward from both sides of the flange at the upper part thereof, on the outer ends of which are formed the teeth 20. The teeth 20 are separated by slots 22 and, together with the portions adjacent thereto, constitute what may be termed the stationary cutter, the outer surface of which is shown in Figure 2 as convex and as sloping down from a central crest 24, and this surface during the process of shaving engages the surface to be shaved. The lower surfaces of both sets of teeth 20 are shown as lying in the same plane. As a consequence of these configurations, and as also clearly appears from Figure 2, the teeth 20 are tapered outwardly and they are shown as very thin, particularly at their end portions, such thinness of course being desirable because it permits of close shaving, which requires that the cutting take place close to the surface to be shaved and consequently that the region of the cutting, which in the construction disclosed is at the inner surface of the teeth 20, be close to such surface. In order at least partly to overcome the disadvantages of having the cutting teeth so thin, the stationary cutter may be reinforced by having its end portions raised into ribs as shown at 24.

Positioned on each side of the member 12 is an element 26 that I may term a "spacer" because of its spacing function, as will appear, and on the outer side of each spacer is positioned a guard member 28. As shown in the drawings, my construction is such that all of these elements may be united in a single assembly operation such as by merely passing one or more rivets 30 through registering openings in the legs 16 and 18 of the member 12, and in the spacer and guard members 26 and 28.

It will be observed that when the component elements of the fixed parts of my shaving head are assembled in their proper operative relation there is a hollow space in the shaving head that is open at the bottom and limited at the top by the rib portion 14 of the member 12, and that, due to the fact that the spacers 26 extend only part of the distance to the top, lateral channels are formed beneath the tooth portions of the member 24. Within the space just described is positioned a cutter denoted in general by 32 and comprising a central portion 34 carrying two laterally disposed tooth portions 36 separated by a channel 38, this channel being adapted to re-

ceive the rib 14 of the member 12 in slidable relation. The toothed portions 36 that are separated by slots 42 and are shown as being spaced farther apart than are the teeth 20 of the shear plate and these toothed portions are shown as positioned in the aforementioned lateral channels.

After assembly of the elements of this fixed part, the cutter is confined within the aforementioned hollow space and cannot be removed therefrom without mutilating the assembly.

Assembly of the parts just described is a very simple matter as it is not necessary to place the parts in the correct relative position during the operations of inserting and heading the rivets 30. In this way I am enabled to manufacture an efficiently operating dry shaver in a very simple and inexpensive manner by an assembly operation of parts each of which is simple and inexpensive to make and which can be easily assembled.

After the riveting operation the complete assembly may be subjected to a finishing operation consisting only of surface grinding, all the other necessary operations having been performed on the individual parts which may also have previously been given the correct heat treatment. It follows that since the fixed portion is composed of separate elements, that each of these elements may be given a heat treatment different from that of the other elements, so that, for instance, these parts that effect the cutting function may be made relatively hard for that purpose, whereas the spacing members, whose function is only that of spacing and holding the other parts in the correct relative position may be made relatively soft and tough, whereby they will add strength to the assembly, other parts of which may be relatively brittle.

By referring to Figure 2 it will further be observed that the teeth 40 are coterminous with teeth 20 and that they are of triangular outwardly tapering contour and that their upper surfaces engage the lower surfaces of the teeth 20 in slidable relation thereto. Because of the triangular contour of the teeth 40 an open channel portion 44 is left on each side of the shaving head and this is found very advantageous for the disposal of shaving waste since these channels are shown merging into openings 46, a pair of which are provided in each guard member 28. For facilitating the outward movement of the waste the upper surface of each spacer plate is shown as inclined and as merging into the lower surfaces of the openings 46, which are similarly inclined.

It is to be understood that the teeth 20 and 40 are provided with cutting edges formed respectively on the lower surfaces of teeth 20 and the upper surfaces of teeth 40 and that these edges cooperate in a shearing action as they are moved relatively to each other.

At its upper portion each guard member is provided with a "shoe portion" that is traversed by a plurality of slots 48 breaking up the shoe portion into a plurality of teeth 50 that are in close adjacency to and in registration with the teeth 20 of the stationary cutter. The teeth 50 have no cutting function but merely serve as an advance portion of the fixed part of the shaving head and to receive in the slots thereof the hairs that are encountered as the shaving device moves over the surface to be shaved. To accomplish the latter function satisfactorily I have shown the teeth 50 as tapered in a horizontal plane at

their outer end portions as shown at 52, with the result that the slots 48 widen or flare outwardly at their entrance portions as indicated at 51, whereby, when the shaver is moved in the direction of the slots, substantially all the hairs encountered will be received in the wide entrance portions of the slots of the shoe portion and will be guided into the narrow portions of the slots 48, from which they will pass directly into the slots 24 of the stationary cutter, at which point they are subjected to a cutting operation. It will be observed that the function of the slots 48 is restricted merely to guiding. It will further be observed that the teeth 50 overhang the walls 15 of the guard members 28, whereby long hairs may enter the slots 52, and that the latter are shown as provided with reinforced portions 54 at each end thereof.

In order to provide for reciprocation of the movable cutter 32 in relation to the stationary cutter the portion 34 of the cutter 32 is shown as provided with a recess 56 into which projects the end 58 of a lever 60 that may be reciprocated or oscillated from any suitable source of power, such, for example, as an electric motor positioned within the handle, and it will be further observed that the portion 34 is made shorter than the channel 38 at both ends so that it will not interfere with the leg portions 16 and 18 of the stationary cutter as the cutter 32 is reciprocated, whereby the ends of the cutter are of forked configuration the prongs of the fork being constituted by extensions of the cutting portions, which in the assembled relation embrace the legs 16 and 18 of the stationary cutter.

Means may be provided to maintain the shearing contact between the teeth 20 and 40, and I have shown means for this purpose in Figure 4, comprising a pair of plungers 62 having enlarged heads 63 that slide within bores 64 provided at any suitable place in the handle, and helical springs 66 positioned within the bores and as pressing the enlarged head 63 outward so as to press the plunger 62 against the cutter 32. Since the outer ends of the plungers 62 are capable of lateral movement I may provide recesses 68 in the cutter 32 into which these end portions may fit. As the cutter 32 is caused to reciprocate by the movement of the lever 58 the plungers 50 will follow the movement of the cutter without interruption of their function of maintaining the contact between the fixed and movable cutting teeth.

The outer ends of bores 64 may be contracted as indicated at 65 and set screws 67 may close the lower end of the bore, whereby the pressure of the springs may be adjusted, while the screws are readily removed for the purpose of inserting the plungers 62 and the springs 66.

In Figure 6 I have shown a construction for the teeth of the guard member 28 which is similar in every way to that shown in Figure 5 except that the outer portions of the teeth 50 are shown as uniformly tapered instead of as tapering along the curves shown in Figure 5, as a result of which the end portions 52 of the teeth 50 may be described as truncated wedges. The effect of this construction, in general, is however identical with that of the construction shown in Figure 5.

In Figure 7 I have shown a construction that differs from that of Figure 1 only in that the outer face of the shear plate and the guard members lie in the same plane instead of being convexly contoured while the lower faces of the two

sets of teeth 20" lie in divergent planes. The parts in this figure have been numbered similarly to those of Figures 1 to 5 except that the numerals are double primed and it is consequently believed to be unnecessary to describe the parts of this figure in detail.

It will be understood that while I have herein disclosed several embodiments of my invention that this disclosure is for purposes of illustration only, and that my invention may be embodied in many other forms without departing from the spirit thereof, as will be obvious to those skilled in the art, and that the disclosure herein is by way of illustration merely and is not to be construed in a limiting sense, and that I do not limit myself other than as called for by the prior art.

Having thus described my invention and illustrated its use, what I claim as new and desire to secure by Letters Patent, is:

1. A dry shaver comprising a face engaging plate having supporting legs with flat sides depending therefrom adjacent its ends, and a cutter member mounted for movement relatively to the face engaging plate and having spaced projections extending forwardly and backwardly therefrom and having flat inner sides to embrace the legs during its movement and to engage their flat sides in sliding contact.

2. A shaving head comprising a slotted stationary cutter, a movable cutter slidable in relation to said stationary cutter, a slotted guard member positioned on each side of said stationary cutter and the slots of said guard members being in registration with the slots of said stationary cutter, a spacer member positioned intermediate each guard member and the stationary cutter, and connecting elements each engaging said stationary cutter, said guard members and said spacer members and uniting them into a single unit.

3. A dry shaver comprising a face engaging member, guards laterally thereof, and spacer members between the guards and the member, and means for securing all the said parts in assembled relation, said means passing through all of said parts.

4. A dry shaver comprising a stationary cutter, a movable cutter therebeneath, guards laterally thereof, and spacer members for the guards positioned below the movable cutter in spaced relation to provide a space beneath the movable cutter, the guards being cut away opposite said space for the discharge of the cut hairs and the upper surface of each spacer member and the lower wall of each cut away guard portion being inclined and merging into each other so as to form a single surface.

5. A dry shaver having a central member of inverted U-shape with cutting teeth extending laterally from both sides of the U and having legs of substantially uniform width, a guard member positioned on each side of said central portion and in parallel relation thereto, the inner wall of each said guard member being flat and having a slotted portion which is positioned in close adjacency to said cutting teeth, a pair of spacer members of substantially uniform thickness, one disposed between each of said guard members and the legs of the central member so as to fill the space therebetween except at the upper portion where a space is left, and whereby a space is formed between said spacer members and said legs, a cutter element disposed within said space in the upper portion and having cutting teeth in

slidable contact with said cutting teeth of said central member, and connecting elements each passing respectively through the guard members, the spacers and the leg of the U and serving to unite them.

6. In a dry shaver head, a stationary cutter, a movable cutter, and fixed members carried by said stationary cutter, a channel for receiving shaving waste bounded by an outer wall provided with a discharge opening, a continuous fixed inner and bottom wall extending from end to end of the channel and abutting said outer wall, and the upper wall being constituted by the outer wall of said movable cutter and by the outer walls of said fixed members over which the ends of said cutter slide, and the said upper wall abutting the outer wall at one side thereof and abutting the inner and bottom wall at the other side thereof, whereby shaving waste is excluded from the interior of the shaver head.

7. In a dry shaver head, a toothed face-engaging member, a U-shaped portion of substantially uniform thickness depending from said member, a channeled toothed cutter adapted to slidably receive the bight portion of said U within the channel thereof, said cutter being adapted to cooperate with said member to effect a shearing action, and the side walls of the channel of said cutter being extended so as to slidably contact the side walls of the leg portion of said U, and the channeled portion of the cutter being of such length that as it moves slidably in relation to said bight portion, the aforesaid extensions will always be maintained in slidable contact with the side walls of said leg portions.

8. A stationary cutter element for a dry shaver comprising a face engaging member, teeth projecting laterally from one edge thereof and substantially straight supporting legs depending therefrom underneath and adjacent the ends of said member, said legs being of substantially uniform rectangular cross section and of uniform thickness, and a flange of the same thickness as said legs running along the lower side of said member in alignment with and between said legs, whereby a cutter having a channel therein of a width slightly greater than the thickness of the flange and the legs, may receive said flange and portions of the legs within its channel and may be moved relatively to said stationary cutter element with the side walls of the channel sliding over the side walls of said flange and of said legs.

9. A movable cutter for a dry shaver comprising a member channeled centrally of its width, a relatively thin flange forming a bottom wall for the channel at the mid portion of the channel and projecting downwardly beneath the channel in said member, and teeth projecting laterally of the channel, the flange being shorter than the channel, and being of a thickness substantially equal to the width of said channel, whereby said cutter is adapted to receive within its channel a rib and leg portions on a stationary cutter, which rib and leg portions have a thickness slightly less than the width of the channel.

10. A dry shaver having a central member of inverted U-shape with cutting teeth extending laterally from both sides of the U and having legs of substantially uniform width, a guard member positioned on each side of said central portion and in parallel relation thereto, the inner wall of each said guard member being flat and having a slotted portion which is positioned in close adjacency to said cutting teeth, a pair of spacer members of substantially uniform thickness, one dis-

posed between each of said guard members and the legs of the central member so as to fill the space therebetween except at the upper portion where a space is left, and whereby a space is formed between said spacer member and said legs, a cutter element disposed within said space in the upper portion and having cutting teeth in slidable contact with said cutting teeth of said central member, and connecting elements each passing respectively through the guard members, the spacers and the leg of the U and serving to unite them, and said cutter member having a flange thereon slidable in the space between said spacer members and said legs.

11. A stationary cutter element for a dry shaver comprising a face engaging plate, teeth projecting laterally from the opposite edges thereof, and substantially straight supporting legs depending therefrom intermediate of the teeth, said legs being of a substantially uniform rectangular cross section throughout and having flat side faces, and the side leg faces disposed on one side of the element lying in one plane and the side leg faces disposed on the other side of the element lying in another plane, whereby said legs are adapted for the attachment of flat plates overlying the side leg faces on opposite sides of said legs.

12. In a shaving device: a shaving head comprising a stationary cutter, a movable cutter in sliding contact with said stationary cutter, a handle provided with a recess for seating said shaving head, means in said handle extending into engagement with said movable cutter for reciprocating it relatively to said stationary cutter, means for maintaining the sliding contact of said movable cutter and said stationary cutter, said means comprising a pair of plungers, a mounting for each of said plungers in said handle comprising a shoulder on the handle, an abutment on the plunger, and an abutment on the handle, spring means acting between said abutment on the handle and the abutment on the plunger for urging the abutment on the plunger against the shoulder, said abutment on the plunger and the shoul-

der being relatively so contoured that the plunger may have limited pivotal movement relatively thereto, said plungers being spaced from each other in the direction of movement of said cutter, and recesses in said movable cutter, each adapted to receive the end of one of said plungers.

13. A dry shaver comprising a face engaging member having flat face portions thereon, flat-faced guards laterally thereof, and flat-faced spacer members between the guards and the face engaging member, and a single means for securing all the parts in assembled relation with their flat portions in superposed adjacency.

14. A dry shaver having a central member of inverted U-shape with cutting teeth extending laterally from both sides of the U, a guard member positioned on each side of said central portion and in parallel relation thereto, the inner wall of each said guard member being flat and having a slotted portion which is positioned in close adjacency to said cutting teeth, a pair of spacer members of substantially uniform thickness disposed between each of said guard members and the central member so as to fill the space therebetween except at the upper portion where a space is left, a cutter element disposed within said space and having cutting teeth in slidable contact with said cutting teeth of said central member, and connecting elements each passing respectively through the guard members, the spacers and the leg of the U and serving to unite them.

15. A dry shaver comprising a stationary cutter, and a movable cutter therebeneath, having teeth projecting laterally therefrom, a spacer plate beneath the movable cutter and a guard positioned laterally of the movable cutter, the spacer plate being of a width to position the guard in sufficiently close adjacency to the ends of the teeth of the stationary cutter to prevent the entry of skin into the space therebetween, and means interconnecting said stationary cutter, said guard and said spacer plate.

GODFREY DALKOWITZ.
